US00D497120S1

(12) **United States Design Patent** (10) Patent No.: **US D497,120 S**
Chia et al. (45) Date of Patent: **** Oct. 12, 2004**

(54) **JEWELRY COMPONENT**

(76) Inventors: **Meang K. Chia**, 412 W. 6th St., Suite 1104, Los Angeles, CA (US) 90014; **Cheo K. Chia**, 412 W. 6th St., Suite 1104, Los Angeles, CA (US) 90014; **Huy K. Chia**, 412 W. 6th St., Suite 1104, Los Angeles, CA (US) 90014

(**) Term: **14 Years**

(21) Appl. No.: **29/149,700**

(22) Filed: **Oct. 11, 2001**

(51) LOC (7) Cl. **11-01**

(52) U.S. Cl. **D11/93**

(58) Field of Search D11/1-26, 48, D11/76, 93-94; 59/78-90; 63/1.11-6.9, 11, 20

Primary Examiner—R. Seifert

(74) Attorney, Agent, or Firm—Ladas & Parry LLP

(57) **CLAIM**

The ornamental design for a jewelry component, as shown and described.

DESCRIPTION

FIG. 1 is a perspective view of a first embodiment of a jewelry component showing our new design;

FIG. 2 is a top plan view of the first embodiment;

FIG. 3 is a front elevational view of the first embodiment, the rear, left, and right elevational views being mirror images;

FIG. 4 is a perspective view of a second embodiment of a jewelry component showing our new design;

FIG. 5 is a top plan view of the second embodiment;

FIG. 6 is a front elevational view of the second embodiment, the rear, left, and right elevational views being mirror images;

FIG. 7 is a perspective view of a third embodiment of a jewelry component showing our new design; and,

FIG. 8 is a top plan view of the third embodiment.

It being understood that the broken lines are for illustrative purposes only and form no part of the claimed design.
